UNITED STATES PATENT OFFICE

2,167,364

RAILWAY HOPPER CAR

Albert A. Johnson, Kew Gardens, N. Y.

Application April 12, 1937, Serial No. 136,257

4 Claims. (Cl. 105—247)

This invention relates to improvements in railway cars, and more particularly to a railway hopper car for the expeditious and economic transporting and handling of loose citrus fruit or the like from its geographical location of growth to distant places of distribution and consumption.

It is the general practice in the transporting of citrus fruits and other similar edibles to hand pack the same in crates at the location of their growth, manually stack the crates in refrigerator cars for shipment, and manually unload the crates at their point of destination. Such method of packing, car loading and unloading is costly, due to the cost of packing materials, manual labor involved in handling, and demurrage charges by the railroads for any excessive time required in the use of a car which may be caused by the lessee during loading and unloading operations. It is therefore the purpose of this invention to overcome this economic problem, and which is accomplished by reason of the novel features in refrigerator car construction and unloading means therefor which enables the handling and shipment of citrus fruits in loose condition in carload lots without injury to the fruit so handled and shipped.

Another feature of the invention resides in apparatus of the above mentioned kind which enables the shipment of carload lots of ripe or nearly ripe citrus fruit, rather than unripened, due to the fact that less time is required in the shipment of the fruit from its source of growth to its terminal of distribution and sale in smaller lots.

While I have set forth above the broad aspect of the features of my invention, other features appear in the following specification, pointed out in the appended claims, and illustrated in the accompanying drawings, in which,

Figure 1 is a side elevational view of my improved refrigerator railway car coupled with the unloading apparatus.

Figure 2 is a horizontal sectional view on the line 2—2 of Figure 1.

Figure 3 is an enlarged horizontal sectional view on the line 3—3 of Figure 2, but showing the closure plates closing the fruit discharge outlet and the loading apparatus disconnected therefrom.

Figure 4 is a fragmentary horizontal sectional view on the line 4—4 of Figure 3.

Figure 5 is an enlarged fragmentary vertical sectional view through the refrigerator car extending from one end to a point slightly beyond

the mid portion thereof, the parts being in position for loading of the car.

Figure 6 is a vertical transverse sectional view on the line 6—6 of Figure 5.

Figure 7 is a detail horizontal sectional view on the line 7—7 of Figure 5.

Figure 8 is a detail vertical sectional view through a modified form of hopper drive.

Figure 9 is a fragmentary horizontal sectional view on the line 9—9 of Figure 8.

While I shall proceed with the description of my invention for use in the shipment of citrus fruits such as oranges, grapefruits and lemons, I wish it to be understood that the apparatus about to be described may be employed in the handling and shipment of other loose articles by carload lots.

Referring to the drawings by reference characters, the numeral 10 designates my improved refrigerator railway car in its entirety, which includes a box like body 11 having insulated side walls 12—12, insulated end walls 13—13, an insulated bottom wall 14 and an insulated top wall 15. The opposite ends of the car body 11 are provided with spaced vertical partitions 16 which divide the main inner compartment of the body from refrigerator compartments 17 at the ends of the body into which the cooling medium such as ice, for the cooling of the body is adapted to be located. The side walls 12—12 of the car body 11 are provided with the usual door openings 18—18, the same being located centrally of the length of the car body, which door openings are closed by planks 19 preparatory to the loading of the body. The plank 20 bridging each door opening 18 approximately midway of the same is fixed across the door opening for a purpose to be presently explained, whereas the other planks designated 19 are removable for permitting ingress and egress to the interior of the car body when empty or when partially empty. Whereas, I have not illustrated the usual refrigerator door for closing the door openings 18—18, it will be understood that the car will be provided therewith to effectively seal the openings against entry of heated air into the car body.

The central portion of the bottom wall 14 of the car body is provided with a well 21, the bottom wall of the said well being provided with an opening 22 and bolted to the well bottom and depending therefrom is a short length discharge spout 23, the lower end being provided with a flange 24 for removably supporting a closure plate 25, the said plate being provided with a pair of hook lugs 26 for engagement with the

flange 24 and with a slot 27 extending inwardly from its periphery for receiving a pivoted bolt 28, the said bolt being carried by the spout and having a clamping nut 30 thereon for securing the closure plate in position over the lower end of the discharge spout 23. It will be appreciated that the closure plate 25 may be removed by loosening the nut 30, swinging the bolt 28 out of the slot 27 and then disengaging the hooked lugs 28 from the flange 24.

Fixedly mounted in the well 21 is an annular casing 31, the same being concentric with respect to the discharge opening 22. Rotatably mounted within the casing 31 by means of roller bearings 32 is an annular hopper 33, the open top of which supports a removable grate disk 34 secured to the top of the hopper by removable bolts or screws 35. The grate disk 34 is provided with annular rows of staggered openings 36, which openings are of a size to permit of the free passage of the individual articles of fruit which are to be shipped in the car. The grate is made removable in order that a grate with relatively large openings may be provided for the passage of grapefruit therethrough, medium size openings for oranges, and smaller openings in the event that the car is to be used for the shipment of lemons. The central portion of the grate disk 34 is provided with a crown 37, the top of which is on a plane approximately with the plane of the peripheral edge of the grate disk, the grate disk being inclined outwardly from a point adjacent the crown in order that fruit rolling onto the grate disk will gravitate toward the annular series of staggered openings 36. The hopper 33 is provided with an integral collar 38 having an annular groove or channel 39 in its peripheral edge for the reception of a cable 40, which cable is adapted to be extended through one side of the car body with its ends connected so as to constitute a belt, which may be connected up with a driving pulley or actuated by hand power to impart rotation to the hopper 33 during an unloading operation as will be clearly described hereinafter.

For the purpose of guiding and protecting the fruit from injury as it passes from the hopper 33 to the discharge spout 23, there is provided rubber or other yieldable fingers 41 at the discharge outlet of the hopper, the said fingers being arranged in radial formation. These fingers prevent butting contact of fruit rolling down the hopper from opposite sides, as such contact may cause injury to the fruit. The interior of the car body 11 is provided with inclined perforated flooring 42 which is spaced from the bottom wall 14 and which flooring is provided with a central opening 43 of a size approximating the diameter of the hopper 33 and disposed in concentric relation thereto. The flooring 42 is inclined away from the opening 43, and the angle of inclination is such that articles supported by the flooring 42 will gravitate toward the opening 43 for passage through the hopper 33. The inclined flooring 42 at the opening 43 is slightly above the plane of the top of the hopper 33 and interposed therebetween for sliding movement to a position to close the opening 43 is a pair of opposed closure plates 44-44. Each closure plate 44 is of identical construction and actuated by a like mechanism and each is adapted to overlie one half of the discharge outlet 43 when the closure plates are in closing position with the stop lugs 114 carried thereby abutting a fixed stop 115. When in open position, the plates 44

are disposed clear of the opening 43 as illustrated in full lines in Fig. 4 of the drawings. Each plate 44 is slidably mounted in guide tracks 45 provided on the under side of the floor 42 and carried by the outer side of the plate adjacent opposite side edges thereof are rack bars 46, the teeth of which mesh with pinions 47 fixed to a shaft 48 which extends transversely of the car body and is journaled in bearings 49 carried by the side walls 12-12. The ends of the shaft 48 terminate in recesses 50 provided in the side walls 12, the recesses being normally covered and concealed by removable plates 51. The ends of the shaft 48 are squared as at 52 so that when the plates 50 are removed as shown in Figure 4 of the drawing, a crank handle 53 may be applied to either of the squared ends 52 and manual rotation can be imparted to the shaft 48 causing rotation of the pinion 47 and thus impart sliding movement to the closure plate 44 to either open or closed position. When the car body is loaded with fruit, the plates 44 are in closed position and prior to the unloading operation, the same are manually moved to open position in order to expose the perforated grate 34 to the contents of the car body. An abutment 54 disposed in the path of the outer end of each closure plate 44 serves to limit the opening movement of the closure plates, while closing movement of the plates is limited by contacting engagement of the stops 114 on inner ends of the said plates with the fixed stop 115 as illustrated in Figure 6 of the drawings.

The interior of the car body 11 is divided by a horizontal partition which divides the interior 35 of the car body into a lower storage compartment 55 and an upper storage compartment 56. The horizontal partition is made up of two half units, each unit being disposed at opposite sides of the door opening 18. Each unit is composed 40 of spaced trap doors 57, there being three of such doors embodied in each unit and which are disposed in spaced relation and pivoted on the same plane as at 58. Also pivoted on substantially the same plane as the trap doors 58 is one 45 central door 59 and a similar door 60 disposed intermediate the central door 59 and the end wall of the car body. These doors are adapted to be raised to the position shown in Figure 5 during a loading operation of the lower compartment 55, and the same are disposed in vertical alignment with the filling openings 61 provided in the top wall 15 of the car body. Flexible filling hose 62 are inserted through the opening 61 down through the upper compartment 56 55 and into the lower compartment 55 during a loading of the lower compartment. When the lower compartment has been filled, the hose 62 are lifted, the doors 59 and 60 closed, and the discharge end of the hose left in the upper compartment 56 will effect a filling of the upper compartment. When the car is completely filled, and the hose 62 withdrawn from the openings 61, hatch doors 116 are applied over the openings as illustrated in Figure 2. When the doors 59 65 and 60 are in closed position, they rest upon cleats 63 and 64 respectively, the cleats 63 being secured to the fixed plank 20 and the cleats 64 to opposite side walls 12-12 of the car body. The doors 59 and 60 are of inverted V-shape in cross section to cause articles to gravitate thereover during the dumping of the contents from the upper compartment 56 to the lower compartment 55.

Fixed inclined partition sections 65 bridge the 75

space between the trap doors 57 and between each end trap door 57 and end wall of the body and coacts with the trap doors, and doors 59 to provide a continuous partition structure as shown in dotted lines in Figure 1 of the drawings. The trap doors 57 of each half partition unit are simultaneously operated to open and closed positions by a mechanism now to be explained. The doors 57 and 60 and fixed partition sections 65 have openings 126 therein for cooling and ventilating purposes between the lower compartment 55 and the upper compartment 56.

Journalized in bearings 66 which are secured to the inner side walls 12 within the compartment 55 is a slideable rod 67, while pivotally connected at 68 to the rod 67 are the lower ends of links 69, the opposite ends of the links being pivotally connected to the free ends of the respective pivoted trap doors 57 as at 70. The rod 67 is provided with a rack bar 71 and in view of the fact that two rods 67 are disposed adjacent the respective side walls 12-12 and each being provided with a rack bar 71, I provide a pair of pinions 72 meshing with the respective rack bars as illustrated in Figure 2 of the drawings in order that both racks move simultaneously in the same direction. The pinions 72 are fixedly carried by transversely disposed shafts 73 journaled in bearings carried by the side walls 12-12 of the car body. The ends of the shaft 73 are squared and are disposed in recesses 74 provided in the outer sides of the side walls 12-12, the recesses being normally closed by removable closure plates 75. When it is desired to operate the trap door actuating mechanism, the closure plates 75 are removed and a crank similar to the crank 53 is applied to either of the squared ends of the shaft 73 and rotation imparted to the shaft, which causes the pinions 72 to actuate the rack bars 71 and impart sliding movement to the rod 67 in either of two directions. By sliding the rod 67 in one direction, the doors 57 will be pulled down to the dotted position shown in Figure 5 in order that the load in the upper compartment 56 may be emptied in the lower compartment 55. When in a lowered open position as shown in dotted lines in Figure 5, the trap doors 57 act as inclined extensions for the adjacent stationary partition sections 65. By sliding the rods 67 in an opposite direction, it will be seen that the trap doors 57 may be raised to closed position, as illustrated in full lines in Figure 5 of the drawings.

By providing a horizontal dividing partition 55 within the car body, it is possible to relieve the weight of the load upon the articles of fruit stored in the lower half of the car body, but during unloading operations, it will be seen that after the lower compartment 55 has been partially or fully emptied, the trap doors 57 may be opened to dump the load from the upper compartment 56 into the lower compartment 55 from where the load gravitates toward the discharge opening 43.

For the purpose of cooling the compartments 56 and 55, the partition walls 16 adjacent the ends of the car body are provided with openings 76 which enable cool air from the cooling chambers 17 to enter the respective compartments 55 and 56. Also, by reference to Figure 5 of the drawings, it will be noted that an opening 77 is also provided in the partitions 16 to enable cool air to pass from the compartment 17 into the space between the flooring 42 and the bottom wall 14 of the car body in order to cool the load

from beneath, and permit circulation of cool air up through the perforations in the flooring 42.

After a refrigerator car constructed in accordance with the construction just described has been loaded with citrus fruits such as oranges, 5 grape fruit, or lemons, it is transported over rail to its point of destination and when reaching such destination, there is provided unloading apparatus now to be described.

Referring to Figure 1 of the drawings there 10 is shown an unloading station which includes an underground compartment 78 having a concrete roof 79 which forms part of the road bed of a railroad track 80 laid along the surface of the ground. It will be understood that if the track 15 80 is arranged on an elevated structure, there will be no necessity for providing an underground compartment 78. Whereas any form of conveyor 20 may be associated with the discharge spout 23 to receive the individual units discharged therefrom, I have illustrated in the drawings, a discharge tube 90 having an enlarged skirt portion 107 which telescopes the spout 23 during an unloading operation.

Assume that a coupling is to be made between 25 the outlet spout 23 of the car and the unloading tube 90 of the unloading apparatus and it is desired to unload the contents of the railway car 10. An attendant first removes the closure plate 25 after which he removes the plates 51 30 from one side of the car to gain access to the squared ends 52 of the shaft 58. A crank is applied to the squared ends of the shaft 48 and the shaft rotated to cause the pinions 47 acting on the rack bars 46 to move the slide closure plates 35 44 from closed position to open position, thus exposing the perforated grate disk 34 to the contents of the lower compartment 55 of the car. The contents, be they oranges, grapefruits, or lemons, will gravitate through the openings 36 40 in the grate 34 and to prevent clogging, rotation is imparted to the grate through the hopper 33 by means of the endless driven cable 39. The fruit after passing through the openings 36 enters the hopper 33, passes down through the outlet 45 spout 23 into the unloading tube 90 and out through the lower discharge end thereof where it is received in a portable receptacle placed therebeneath. This unloading continues until the entire or partial contents of the lower compartment 55 has been emptied, after which 50 cranks may be applied to the squared ends of the shafts 73 and the trap door actuating mechanism operated to cause the trap doors 57 to swing down in order to dump the load contained within the upper compartment 56 into the lower compartment 55, thus continuing the flow of fruit through the unloading tube 90 until the entire contents of the car have been discharged.

After the completion of the unloading operation 60 the unloading tube is disconnected from the discharge spout 23, the cover plate 25 which was previously removed from the discharge spout 23, the cover plate 25 which was previously removed from the discharge spout 23 is replaced and the 65 closure plates 44 moved to closed position to overlie the grate 34.

In Figures 8 and 9 of the drawings, I have 70 illustrated a modified form of hopper drive which may be employed in lieu of the cable drive hereinbefore shown and described. In this form, 116 designates an upstanding bearing rising from the car bottom 117, the upper face of which is provided with a ball race groove 118 having ball 75

bearings 119 therein. A rotating hopper 120 is supported upon the ball bearings 119 and is provided with an annular ball race groove 121 for receiving the said ball bearings. Fixed to the lower outlet end of the hopper is a ring gear 122 which has constant mesh with a worm 123 fixed to a driven rotatable shaft 124. The shaft 124 is mounted in bearings 125 which may be mounted on the car bottom 117, while one end of the shaft 124 is adapted to extend beyond one side of the car to be connected with a source of power (not shown) for driving the same.

From the foregoing description, it will be seen that I have provided a refrigerator railway car which will enable the transportation of citrus fruits in bulk without injury to the fruit either during loading, in transit, or during unloading, thus eliminating the present practice of initially crating the fruit, packing the crates in cars by manual labor and manually removing the same at their point of destination. The system which I have described and shown in the drawing not only reduces the cost of shipment of citrus fruits or like articles, but permits of the shipment of the fruits in ripe or near ripe condition, due to the expeditious method of unloading of the car at its point of destination. Also, a greater volume of fruit may be shipped in my improved car than in the ordinary refrigerator car of like size, due to the elimination of waste space taken up by crates and spaces therebetween.

While I have shown and described what I consider to be the most practical embodiment of my invention, I wish it to be understood that such changes and alterations as come within the scope of the appended claims may be resorted to if desired.

Having thus described the invention, what I claim as new and desire to secure by Letters Patent of the United States, is:

1. A railway car for the shipment of individual units in loose condition comprising a car body having a discharge opening in the bottom thereof, flooring inclined upwardly from said discharge opening, a rotatable grate mounted in said discharge opening and having grate openings therein of a size to admit of the free passage of individual units therethrough, means operable for imparting rotation to said grate, and slide closure means operable exteriorly of said car body for

closing said discharge opening to shut off the flow of units to said grate.

2. A railway car for the shipment of individual units in loose condition comprising a car body having a discharge opening in the bottom thereof, flooring inclined upwardly from said discharge opening, a rotatable grate mounted in said discharge opening and having grate openings therein of a size to admit of the free passage of individual units therethrough, means operable for imparting rotation to said grate, a hopper disposed beneath said grate to receive the units passing through said grate openings said hopper having a central outlet, a discharge pipe depending from the bottom of said body and communicating with the outlet of said hopper, and flexible guide members extending inwardly from the walls of the outlet of said hopper and freely terminating adjacent the axis of the said outlet.

3. A railway car for the shipment of individual units in loose condition comprising a car body having a discharge opening in the bottom thereof, flooring inclined upwardly from said discharge opening, a hopper rotatably mounted in said discharge opening, a substantially dish shape grate member secured to and overlying the open top of said hopper and having grate openings therein of a predetermined size to permit of the free passage of individual units therethrough, means for imparting rotation to said hopper, and slide closure means manually operable from the exterior of said car body for closing said discharge opening.

4. A railway car for shipment of individual units in loose condition comprising in combination, a car body having a discharge opening in the bottom thereof, an annular hopper member having its open top disposed below and in vertical alignment with said opening, means for rotatably supporting said hopper member, means for imparting rotation to said hopper member, slide closure means being mounted for operation on a plane intermediate the bottom of said body and the top of said hopper member, and rack and pinion means manually operable from the exterior of said car body for moving said slide closure means to open position clear of said discharge opening and to closed position beneath said discharge opening.

ALBERT A. JOHNSON. 50
